(57) **CLAIM**

The ornamental design for a case for a personal digital assistant, as shown and described.

DESCRIPTION

FIG. 1 is an oblique view of a case for a personal digital assistant showing our new design;

FIG. 2 is a left side elevational view thereof, the right side being a mirror image of the left side;

FIG. 3 is a top plan view thereof;

FIG. 4 is a front elevational view thereof;

FIG. 5 is a rear elevational view thereof; and,

FIG. 6 is a bottom plan view thereof.

The broken lines are shown in the views for illustrative purposes only and form no part of the claimed design.
